UNITED STATES PATENT OFFICE.

CECELIA H. STEWART, OF PITTSBURGH, PENNSYLVANIA.

DESIGN FOR A COVER CASING FOR MATCH PACKAGES.

Application filed July 31, 1925. Serial No. 14,285. Term of patent 3½ years.

To all whom it may concern:

Be it known that I, CECELIA H. STEWART, a citizen of the United States, residing at Pittsburgh, in the county of Allegheny and State of Pennsylvania, have invented a new, original, and ornamental Design for a Cover Casing for Match Packages, of which the following is a specification, reference being had to the accompanying drawing, forming a part thereof.

Fig. 1 of the drawing is a face view to enlarged scale of a cover casing for match packages, the casing being unfolded, and Fig. 2 is an edge view thereof indicating the relative thickness of the casing.

The shading on the drawing is intended to indicate contrasting colors.

I claim:

The ornamental design for a cover casing for match packages substantially as shown and described.

CECELIA H. STEWART.
